United States Patent Office

Des. 183,642
Patented Sept. 30, 1958

183,642

ELECTRIC FURNACE

Edgar C. Worden, Cedar Grove, N. J., assignor to Synthetic Mica Corporation, Caldwell Township, N. J., a corporation of New York

Application August 2, 1956, Serial No. 42,491

Term of patent 14 years

(Cl. D81—1)

FIG. 1.

FIG. 2.

FIG. 3.

FIG. 4.

Fig. 1 is a plan view of an electric furnace;
Fig. 2 is a side elevational view of the furnace shown in Fig. 1;

Fig. 3 is an end elevational view of the furnace shown in Figs. 1 and 2; and

Fig. 4 is a perspective view of the furnace shown in Figs. 1, 2 and 3.

I claim:

An ornamental design for an electric furnace, substantially as shown.
